HOLDER FOR A BEVERAGE CONTAINER OR THE LIKE

Grady W. Shuford, Forest City, N.C., assignor to HHS
Investors, Inc., Forest City, N.C.

Filed July 29, 1971, Ser. No. 167,546

Term of patent 14 years

Int. Cl. D7—99

U.S. Cl. D44—21 A

FIG. 1 is a top front perspective view of a holder for a beverage container or the like showing my new design;

FIG. 2 is a side elevation thereof;

FIG. 3 is a front elevation thereof;

FIG. 4 is a top plan view thereof; and

FIG. 5 is a back elevation thereof.

I claim:

The ornamental design for a holder for a beverage container or the like, as shown.
